Attorney

UNITED STATES PATENT OFFICE.

WILLIAM N. BEARD, OF FORT WORTH, TEXAS.

METHOD AND MEANS FOR PRINTING HEADINGS.

Application filed March 12, 1927. Serial No. 174,907.

This invention relates to new and useful improvements in methods and means for printing headings on syndicated sheets.

It is a common practice for a number of 5 newspapers to contain a section of the same printed sheets, such as a comic section. All of these sheets are usually printed by one concern, with the title or name of the individual publication printed on the sheets 10 which are intended therefor. This requires a separate set of plates for each individual paper, and, besides the expense of providing these plates, a great deal of time is lost in changing the plates on the press. Such 15 sheets are usually printed in two or more colors, and when one set of plates is removed, it generally takes approximately thirty minutes to make the next set ready on the press so the colors will register properly.

20 The object of the invention is to provide means for printing titles or headings on syndicate sheets and obviating the expense of the methods commonly used.

Plates for such sheets are usually cast in 25 stereotype molds from "mats", and particular object of the invention is to provide means whereby it is only necessary to cast one set of key or page plates for the several publications.

30 Another object is to provide a separate title plate for each newspaper, which plate may be easily removed so that another may be substituted, without disturbing in any way the page plates which remain stationary 35 on the press during the printing of sheets for the different newspapers.

A further object is to provide means for casting a plurality of different headings in an integral plate formed in the same mold 40 used for the page plates, the said plate being severed with a saw between the said headings to provide separate title plates.

45 A construction designed to carry out the invention will be hereinafter described together with other features of the invention.

The invention will be more readily understood from a reading of the following specification and by reference to the accompanying drawings, in which an example of 50 the invention is shown wherein:

Figure 1 is a face view of a plate containing a plurality of different headings.

Fig. 2 is a similar view of a page plate and a title plate mounted on a press in operating position, and

Fig. 3 is a detail of one of the clamps.

In the drawings the letter A designates the bed or cylinder of a printing press, which latter may be a cylinder or a bed and platen press. A page plate 10 is cast in the 60 usual manner and mounted on the press. The said plate may be secured in a stationary position in any suitable manner, but for the purpose of illustration I have shown the lower edge of the plate abutting a retaining bar B, with the longitudinal edge of the plate beveled for receiving a plurality of clamps 11. As is best shown in Fig. 3, each clamp is slideable on an elongated screw 12 extending longitudinally of 65 a slot 13 in the member A. An adjusting nut 14 is mounted on the screw behind the clamp for holding the latter against the beveled edge of the plate.

As will be seen in Fig. 1, seven different 70 headings may be cast in a plate 15 which is the same size as the page plate 10. The same stereotype mold may be used for both plates, which obviates additional expense in this respect. The longitudinal edges of the 75 plate 15 are beveled to conform to the corresponding edges of the plate 10, and the said plate 15 is sawed along the lines 16 whereby each heading is contained on an individual title plate 17.

80 After the plate 10 is once mounted on the press it will be seen that it is only necessary to mount a title plate 17 above the same. The said title plate may be easily mounted and held in place by a suitable retaining 85 member C and a clamp 18 on each side engaging the beveled edge. The clamps 18 are similar to the clamps 11, and after the required number of sheets have been run off with this heading, it is only necessary to 90 loosen the clamps 18 and remove the title plate. It is obvious that this may be readily done without disturbing the plate 10, and by substituting a different title plate the 95 operation of the press may be resumed with a 100 minimum of loss of time.

By my improved method there is no time lost registering plates with regard to colors, once the page plates are properly mounted on the press. Furthermore, a great deal of 105 time and money is saved in obviating the need of separate page plates for each newspaper. It will be seen that I accomplish the same result with only one set of page plates used in conjunction with separate title 110 plates.

The invention includes all such changes,

modifications and alterations as come within the scope of the appended claim.

What I claim is:

The method of printing syndicated pages which consists in casting color page plates, then casting a plurality of different headings in a single plate, then severing the said single plate at a point between the said headings to form a plurality of separate title plates, then mounting the color page plates on a

printing press and registering the same then mounting a title plate at the head of one of the page plates, then printing a run of pages, then removing said title plates without disturbing the page plates or the register thereof, and then continuing the printing operation as before. 15

In testimony whereof I affix my signature.

WILLIAM N. BEARD.
